(57) **CLAIM**

The ornamental design for a cylinder electronic scale, as shown and described.

DESCRIPTION

FIG. 1 is a perspective view of a cylinder electronic scale showing my new design;

FIG. 2 is a front side view thereof;

FIG. 3 is a left side view thereof;

FIG. 4 is a top plan view thereof; and,

FIG. 5 is a bottom side view thereof.

The broken lines shown herein are for illustrative purposes only and form no part of the claimed design.
